W. J. Spangler

UNITED STATES PATENT OFFICE.

JAMES MILLER, OF DETROIT, MICHIGAN.

TELEPHONE MOUTH-PIECE.

SPECIFICATION forming part of Letters Patent No. 337,972, dated March 16, 1886.

Application filed May 13, 1885. Serial No. 165,303. (No model.)

To all whom it may concern:

Be it known that I, JAMES MILLER, of Detroit, in the county of Wayne and State of Michigan, have invented new and useful 5 Improvements in Telephone-Transmitters; and I do hereby declare that the following is a full, clear, and exact description thereof, reference being had to the accompanying drawings, which form a part of this specification.

10 This invention relates to certain new and useful improvements in speaking-tubes for telephone-transmitters and in means for attaching the same; and it consists in the peculiar combinations and the novel construction and 15 arrangements of parts, all as hereinafter more fully set forth and claimed.

In the drawings which accompany this specification, my invention is shown in perspective in Fig. 1, and in section in Fig. 2, to 20 show the means of securing the speaking-tube to the transmitter.

25 A represents a glass tube, conical in form from *a* to the outer end, *b*. From *a* to *c* the side walls of this tube are parallel and terminate in a shoulder extending from *c* to *d*, from which point to the inner or smaller end, *e*, the tube is again conical.

30 B is a wooden plate having an orifice therein, with parallel sides to receive that portion of the tube which is formed with the parallel sides between *a* and *c*.

35 C are metallic fastenings, preferably made of wire in the form shown, extending into the ends of the plate *B* in recesses formed therein for the purpose, and, projecting from the ends of said plate *B*, terminate in hooks *h*, by means of which the device is attached to the front of

the transmitter; and set-screws *k*, passing through the front of the plate, engage with the wire fastenings in their recesses and allow 40 the same to be extended or retracted as may be necessary to bring the axis of the tube into coincidence with the center of the diaphragm in the transmitter.

45 The utility of this attachment to the transmitter will readily be seen by every electrician and user of telephones, for experience has shown that by its use the vibrations of the diaphragm caused by the concussion of the air in talking into the instrument are much 50 more pronounced and distinct, so that talking at long distance can be readily done by speaking in a quite low tone of voice, but distinctly.

What I claim as my invention is—

1. The combination, with the plate *B*, having 55 a parallel-sided orifice and means for attaching said plate to a telephone-transmitter, of the glass mouth-piece *A*, conical in form from *a* to *b*, and with parallel side walls from *a* to *c*, engaging the walls of the orifice in said 60 plate, as set forth.

2. The plate *B*, carrying the glass mouth-piece *A* and having formed therein the recesses, as shown, the fastenings *C*, extending into said recesses and terminating in hooks 65 *h*, and the set-screws *k*, passing through the front of the plate and bearing on said fastenings, all combined, arranged, and operating as set forth.

JAMES MILLER.
